[57] CLAIM

The ornamental design for a game board, as shown and described.

DESCRIPTION

FIG. 1 is a top plan view of a game board, showing our new design, the bottom being plain and unornamented;
 FIG. 2 shows a front view of our claimed design (the rear view being identical thereto); and, FIG. 3 shows a side view of our claimed design (the view from the other side being identical).
